[57] CLAIM

The ornamental design for a pill dispensing package, as shown and described.

DESCRIPTION

FIG. 1 is an end elevational view of a pill dispensing package showing my new design;

FIG. 2 is a top isometric view;

FIG. 3 is a side elevational view;

FIG. 4 is a side elevational view showing the side opposite that seen in FIG. 3;

FIG. 5 is a top plan view;

FIG. 6 is a bottom plan view;

FIG. 7 is a top isometric view showing a modified form of my new design; and

FIG. 8 is a top plan view thereof.

FIG. 1
